UNITED STATES PATENT OFFICE

158,930

UTILITY CASE PIECE OR SIMILAR ARTICLE

Kurt Burgold, Asheville, N. C., assignor to Morgan Furniture Company, a corporation of Delaware

Application June 24, 1948, Serial No. 147,156

Term of patent 3½ years

(Cl. D33—19)

To all whom it may concern:

Be it known that I, Kurt Burgold, a citizen of the United States, residing at Asheville, in the county of Buncombe and State of North Carolina, have invented a new, original, and ornamental Design for a Utility Case Piece or Similar Article, of which the following is a specification, reference being had to the accompanying drawing, forming part thereof.

Fig. 1 is a perspective view of a utility case piece, showing my new design.

Fig. 2 is a perspective view similar to Fig. 1, but with the doors shown in their open position.

I claim:

The ornamental design for a utility case piece or similar article, as shown.

KURT BURGOLD.
